SAFETY CIGARETTE HOLDER

Max V. Compton, Watsonville, Calif., assignor of one-tenth to Gadget-of-The-Month Club, Inc., Los Angeles, Calif., a corporation of California

Application November 1, 1957, Serial No. 693,896

3 Claims. (Cl. 131—174)

Generally speaking, the present invention relates to the cigarette holding art and, more specifically, relates to an improved safety cigarette holder which is especially designed to prevent fires caused by careless smokers who are apt to fall asleep before extinguishing the lighted cigarette.

The primary object of the present invention is to provide a safety cigarette holder which is self-snuffing, whereby unattended lighted cigarettes may be extinguished safely.

Another object of the present invention is to provide a self-snuffing cigarette holder which will permit the free escape of smoke and which will not change the taste of the cigarette.

A further object of the present invention is to provide a safety cigarette holder having frictional cigarette retaining means of improved holding characteristics.

Yet another object of the present invention is to provide a safety cigarette holder including improved cigarette retaining means and actuating means, whereby a cigarette may be quickly and easily inserted into the holder.

It is a further object of the present invention to provide a device of the character set forth in the preceding objects, which is extremely cheap, simple, easy to use and of virtually foolproof construction.

Other and allied objects will be apparent to those skilled in the art after a careful perusal, examination and study of the accompanying illustrations, the present specification, and the appended claims.

To facilitate understanding, reference will be made to the hereinbelow described figures, in which:

Fig. 1 is a perspective view of the safety cigarette holder with a cigarette, shown in phantom, inserted therein;

Fig. 2 is a fragmentary rear elevational view of the cigarette retaining means in a normal position;

Fig. 3 is a fragmentary rear elevational view of the cigarette retaining means, with the movable plunger arm depressing the inverted, substantially U-shaped clip into an oval shape, whereby a cigarette may be inserted therethrough; and

Fig. 4 is a reduced side elevational view of the safety cigarette holder, as shown in Fig. 1.

Generally speaking, the safety cigarette holder of the present invention consists of an elongated, open framework, cigarette-enclosing structure, indicated generally at 5 in Figs. 1 and 4, having an inlet end 7 and a closed end 6. The cigarette holder is of open framework construction in order to allow the smoke to escape freely.

The cigarette enclosing structure 5 consists of radially disposed longitudinal bars 8 and transverse structural support bars 9, as shown in Figs. 1 and 4. It should be noted that the bottom portion of the open framework enclosing structure 5 may be closed in order to provide a trap for the cigarette ashes in other versions of the present invention.

The enclosing structure 5 completely surrounds the cigarette 20 and is normally closed enough to prevent

2

the ingress of combustible material such as blankets, bedsheet, or the like.

The longitudinal bars 8 include perpendicularly bent portions 10 at both ends thereof which are affixed at 5 one end to the ring 11 and to the support ring 12 at the opposite end, as best illustrated in Fig. 1. The ring 11, which effectively defines the closed end 6, is of sufficient diameter so that a match may be inserted in order to light the cigarette 20 within the enclosing structure 5. 10 In other versions of the present invention, the closed end 6 may be hinged in order to facilitate lighting of the cigarette 20 after insertion.

The frictional cigarette retaining means, indicated generally at 13 in Figs. 2 and 3, at the inlet end 6, includes 15 a support ring 12 having an aperture 14 at the top thereof, and a movable plunger arm 15 which is cooperable for actuating the inverted, substantially U-shaped flexible cigarette gripper 16.

The flexible gripper 16 is affixed to the inside of the 20 support ring 12 and is normally elliptical in shape at the top thereof when in a normal or a gripping position, as illustrated in Figs. 1 and 2.

One end of the plunger arm 15 is fixedly attached at 25 17 to the ring 11 and the free actuating end 18 is inserted through the aperture 14 and in contact with the top of the clip 16.

As the plunger arm 15 is depressed the actuating end 18 deforms the top of the clip 16 into an oval shape, as shown in Fig. 3, thereby enabling a cigarette 20 to be inserted therethrough. Once the plunger arm 15 is released the gripper 16 will return to its normal elliptical position, as shown in Figs. 1 and 2, thereby firmly retaining the cigarette within the enclosing structure 5.

The cigarette 20 may be lighted prior to or after insertion in the enclosing structure 5.

The cigarette gripper 16 is preferably made of metal or some other fireproof material so that a lighted cigarette will automatically extinguish itself upon burning back to that point. The compression of the gripper 16 is of such strength that it will not compress the cigarette 20 too much, so as not to affect the inhalation process.

A downwardly directed handle 19 is normally attached adjacent the closed end 6 in order to facilitate the handling of the device. The handle 19 is preferably fixedly attached, although in some versions it may be removably mounted.

Numerous modifications and variations of the present invention will occur to those skilled in the art after a careful study hereof. All such properly within the basic spirit, scope and/or teachings of the present invention are intended to be included and comprehended herein as fully as if specifically described, illustrated and claimed.

The exact compositions, configurations, constructions, relative positionings, and cooperative relationships of the 55 various component parts of the present invention are not critical, and can be modified substantially within the spirit of the present invention.

The embodiment of the present invention specifically described and illustrated herein is exemplary only, and is not intended to limit the scope of the present invention, which is to be interpreted in the light of the prior art and the appended claims only, with due consideration for the doctrine of equivalents.

I claim:

65 1. A safety cigarette holder, comprising: an elongated, open framework, cigarette-enclosing structure having an inlet end and a closed end and including radially disposed longitudinal bars and transverse support bars for said radially disposed longitudinal bars; a ring, defining said closed end, whereon said longitudinal bars are fixedly attached at one end thereof; frictional cigarette retaining means at said inlet end, said cigarette retaining means

including a support ring, a cigarette gripper, and actuating means; an aperture on the top of said support ring; said actuating means being cooperable for deforming said cigarette gripper into an oval shape, whereby a cigarette may be inserted therein, and being cooperable, upon release thereof, for allowing said cigarette gripper to return to its normal position thereby enabling a cigarette to be retained within said cigarette enclosing structure, said actuating means comprising a movable arm having one end fixedly attached to said ring at said inlet end and a free actuating end, communicating through said aperture in said support ring, in contiguous contact with the top of said inverted substantially U-shaped cigarette gripper; handle means adjacent said closed end; said cigarette gripper being of fireproof material and being cooperable for extinguishing a lighted cigarette.

2. A safety cigarette holder, comprising: an elongated, open framework, cigarette-enclosing structure having an inlet end and a closed end and including radially disposed longitudinal bars and transverse support bars for said radially disposed longitudinal bars; a ring, defining said closed end, whereon said longitudinal bars are fixedly attached at one end thereof; cigarette retaining means, said cigarette retaining means including a support ring, a cigarette gripper, and actuating means; said cigarette gripper being fixedly attached to the inner surface of said support ring, said cigarette gripper being of fireproof material and being cooperable for extinguishing a lighted cigarette; an aperture on the top of said support ring; said actuating means being cooperable, upon downward movement, for deforming said cigarette gripper into an oval shape, whereby a cigarette may be inserted therein, and being cooperable, upon release thereof, for allowing said cigarette gripper to return to its normal position thereby enabling a cigarette to be retained within said cigarette-enclosing structure; said actuating means comprising a movable arm having one end fixedly attached to said ring at said inlet end and a free actuating end, communicating through said aperture in said support ring, in contiguous contact with the top of said inverted substantially U-shaped cigarette gripper; downwardly directed handle means adjacent said closed end.

support ring, in contiguous contact with the top of said inverted substantially U-shaped cigarette gripper; downwardly directed handle means adjacent said closed end.

3. A safety cigarette holder, comprising: an elongated, open framework, cigarette-enclosing structure having an inlet end and a closed end and including radially disposed longitudinal bars and transverse support bars for said radially disposed longitudinal bars; a ring, defining said closed end, whereon said longitudinal bars are fixedly attached at one end thereof; frictional cigarette retaining means at said inlet end, said cigarette retaining means including a central support ring, whereon the opposite ends of said longitudinal bars are fixedly attached, an inverted, substantially U-shaped flexible cigarette gripper, and manually operable actuating means; said cigarette gripper being fixedly attached to the inner surface of said support ring, said cigarette gripper being of fireproof material and being cooperable for extinguishing a lighted cigarette; an aperture on the top of said support ring; said actuating means being cooperable, upon downward movement, for deforming said cigarette gripper into an oval shape, whereby a cigarette may be inserted therein, and being cooperable, upon release thereof, for allowing said cigarette gripper to return to its normal position thereby enabling a cigarette to be retained within said cigarette-enclosing structure; said actuating means comprising a movable arm having one end fixedly attached to said ring at said inlet end and a free actuating end, communicating through said aperture in said support ring, in contiguous contact with the top of said inverted substantially U-shaped cigarette gripper; downwardly directed handle means adjacent said closed end.
